UNITED STATES PATENT OFFICE.

JOHN RICHARDSON, OF IONIA, KANSAS.

FENCE-POST SOCKET.

SPECIFICATION forming part of Letters Patent No. 364,042, dated May 31, 1887.

Application filed January 20, 1887. Serial No. 224,910. (No model.)

To all whom it may concern:

Be it known that I, JOHN RICHARDSON, a citizen of the United States of America, residing at Ionia, in the county of Jewell and State of Kansas, have invented certain new and useful Improvements in Fence-Post Sockets; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to metallic sockets for fence-posts.

The object of the invention is to effect a saving of wood of which fence-posts are constructed and at the same time to prevent the 20 rotting or decay of the wood at the surface of the ground; and to this end the invention consists in the construction and arrangement, to be hereinafter fully described, and specifically claimed in the claims at the close of this 25 specification.

In the accompanying drawings, Figure 1 is a perspective view of my improved fence post socket. Fig. 2 is a vertical section showing the lower end of the post secured within the 30 socket. Fig. 3 is a horizontal section through the post and chamber. Fig. 4 is a perspective view of the lower end of a fence-post shaped to be inserted in the socket, Fig. 1, from the side.

35 The device is composed of a box-like chamber, A, to receive the lower end of a wooden post, B, and a spur or anchor, C, extending downwardly from the center of the chamber A.

The chamber A comprises a bottom, A', end 40 walls, a, and a side wall, a', all permanently united by casting or otherwise, the end and side walls, a a', either or both, being provided with bolt-holes a", to admit of the insertion of bolts, screws, or nails.

45 Projecting downwardly from the under side of the bottom A' is a spur or anchor, C, of sufficient length, (say eighteen to twenty-four inches,) said anchor being preferably shaped substantially as shown in the drawings—that 50 is to say, the main stem c of the anchor is preferably elliptical in cross-section and tapers toward the bottom, and the side wings, c', are

semi-elliptical in cross-section and also taper from top to bottom. These side wings, c', are about two-thirds the length of the main stem 55 c, and are proportionately narrow at the top, where they join the bottom A' of chamber A, so that said bottom A' will overhang the outer edges of said stem and wings c c'. The fence-post socket so far described is by preference to cast all in one piece, though it will be understood that the parts may be made separately and united by bolts or otherwise.

For use the anchor C is to be driven into the ground its full length, so that the bottom A' 65 will rest upon the surface thereof. The fence-post B, having been properly dressed to snugly fit the chamber A, is then inserted therein, its lower end being supported above the ground and the securing bolts or screws D applied. 70

In some instances I contemplate closing the open side of the chamber A, after the end of the post B is inserted therein, by a detachable covering-plate, a", and this plate a" may be held by the same bolt and nut which are used 75 to secure the post within the chamber, or the opening therein may be tapped, so that the covering-plate will serve the purpose of a nut for the bolt D. I also contemplate forming inward projections a' on the end walls, a', above 80 the bottom A', with which the wood of post B may be caused to lock. This locking action may be attained in various ways—as, for instance, a wedge-shaped spur, A", may be formed integral with the bottom A' and the 85 end of the post be split and spread outward to engage the projections a' in the act of driving it into the chamber, or the end of the post may be split before insertion in the chamber and a wedge A" be driven or drawn in after such 90 insertion, or the end of the post may be shaped to correspond with the shape of the chamber and then inserted therein from the side. In either case the post can be held securely within the chamber by a single screw passing through 95 the side a and into the post.

By the use of my improved fence-post socket I am enabled to save from eighteen inches to two feet in the length of each fence-post B, and, as the lower ends of the posts are supported above the ground and free from contact therewith, they will be much less liable to rot or decay than as though the wood were driven into the ground. 100

I am aware that it is not new to provide the lower end of a timber fence-post with a detachable metallic socket designed to enter the ground; and I am also aware that it has been proposed to provide the upper end of such a socket with an open-sided chamber to receive the lower end of the post proper; but I am not aware that a post-socket has ever before been provided with a post-chamber having horizontally-arranged shoulders or projections designed to prevent the withdrawal of the post end vertically therefrom, or that a post-chamber has heretofore been provided with such horizontally arranged shoulders designed to act in conjunction with a wedge arranged at the bottom of the chamber.

I claim—

1. The combination of a fence-post socket, substantially such as described, having a cham-

ber the side walls of which are provided with horizontally-arranged overhanging shoulders or projections, and the post proper constructed to fit snugly within said chamber, whereby the post is locked against vertical withdrawal from the chamber.

25

2. The combination, with the fence-post squared at its lower end, of a socket, substantially such as described, provided with a chamber having horizontally-arranged overhanging projections a^4 , and a wedge secured within the chamber to split the post and force the wood beneath said overhanging projections.

In testimony whereof I affix my signature in presence of two witnesses.

JOHN RICHARDSON.
